UNITED STATES PATENT OFFICE.

HERBERT E. WHITE, OF YOUNGSTOWN, OHIO, ASSIGNOR TO THE GENERAL FIRE-PROOFING COMPANY, OF YOUNGSTOWN, OHIO, A CORPORATION OF OHIO.

PROCESS FOR MAKING RIBBED EXPANDED-METAL STRUCTURES.

1,145,341.

Specification of Letters Patent.

Patented July 6, 1915.

Application filed May 13, 1913. Serial No. 767,344.

To all whom it may concern:

Be it known that I, HERBERT E. WHITE, a citizen of the United States, residing at Youngstown, in the county of Mahoning and State of Ohio, have invented certain new and useful Improvements in Processes for Making Ribbed Expanded-Metal Structures, of which the following is a specification.

10 The present invention relates to a novel process for making a ribbed expanded sheet metal product known as a ribbed metal lath, which possesses special utility as a supporting and reinforcing element for concrete and other cementitious bodies.

15 The main object of the invention is to provide a simple and practical method of manipulating metal sheets to develop and produce, in a rapid and economical manner, 20 an expanded metal structure having relatively deep grooves between the slitted and expanded portions, said grooves forming ribs which stiffen and otherwise change the general character of the sheet, adapting it 25 for a variety of uses. In the production of these deep ribbed articles, considerable difficulty has been experienced in expanding the slitted portions between the ribs. If the portion intermediate the ribs, be first ex- 30 panded, the act of expansion causes the rib portions to spread apart or move away from one another, requiring complex machinery in order to accommodate this movement. If on the other hand, the act of expanding is 35 concurrent or simultaneous with the formation of the ribs, by causing the slits to open as the metal is taken up in the ribs, the pull on the slitted portion is not equally distributed. The slits nearest the rib will open 40 first; then the next row will start to open, with the result that by the time the slits in the central part of the expanded portion, are fully opened, the metal between the outer slits,—that is, the slits near the edge 45 next to the ribs,—will be greatly strained and distorted. This is particularly true when the slits are to be opened out into diamond shaped figures. The present invention meets this condition by first expanding 50 the slitted portion and making provision for the increased area of the expanded section by causing the slitted portion to move to one side of the plane of the original sheet into an approximately V-shaped formation, 55 while it is undergoing the act of being expanded. Thus, according to the present in-

vention, the expansion of the slitted material is effected without any movement of the uncut area from which the ribs are to be formed.

Accordingly, a distinguishing feature of the present method or process, as compared with other known methods of manufacturing ribbed expanded metal structures, resides in first subjecting the blank sheet of metal to 60 an operation which simultaneously slits and expands certain areas of the sheet and leaves blank unslotted areas between the expanded areas, and subsequently subjects the sheet as thus formed to another operation that 65 channels said blank unslotted areas with relatively deep grooves which produce stiffening ribs for the structure. The effect of this channeling or grooving step is to necessarily displace the unslotted areas or portions of the metal to one side of the plane of the original sheet producing ribs, and to simultaneously exert a lateral draw upon the previously expanded portions with the result of spreading or straightening the latter into substantially the plane of the original sheet. As the unslotted portions of the sheet are folded or drawn into ribs, the area of said uncut portions will contract, but the contraction will be compensated for by 75 the fact that simultaneously therewith the expanded section is taking the form of approximately a plane surface, and its area 80 in the original plane of the sheet is enlarged.

In carrying out the novel process, any 85 suitable instrumentalities or mechanisms may be employed which are available, or can be adapted, for the purpose, but for illustrative purposes there is shown in the drawings, diagrammatically, certain suggested 90 devices that may be employed in connection with the slitting and rib-forming steps, and in these drawings,—Figure 1 is a view illustrative of the preliminary step of the process, namely of a plain sheet metal blank of 95 any predetermined size in section. Fig. 2 is a diagrammatic view illustrative of the special dies that are preferably employed for first subjecting the blank sheet of metal to a combined slitting and expanding operation; the view illustrating the action of the dies in cutting the slits and depressing or displacing the individual strands or cut-out portions. Figs. 3, 4, 5, and 6 are a series of 100 projected sectional views illustrating the 105 preferable manner of slitting and expanding the reticulated or meshed portions of the 110

- sheet, the views showing the progressive development and deepening of the substantially V-shaped or arched meshed webs between the blank unslotted areas. Figs. 7 and 8 are projected sectional and plan views respectively showing the form of the metal sheet as produced by the first step of the process. Fig. 9 is a side elevation of the sheet shown in Figs. 7 and 8. Fig. 10 is a diagrammatic plan view of a type of grooving and spreading machine that may be utilized for the final step of the process. Fig. 11 is a cross sectional view of the slotted and expanded blank illustrating by dotted lines its points of entry into the passes of the primary grooving units. Fig. 12 is a similar view showing the final product with its stiffening ribs and the arched meshed web, or reticulated portions, drawn into their final shape; the view also illustrating the article as it is delivered from the final passes of the grooving and spreading machine. Fig. 13 is a plan view of the final product, viz., the ribbed expanded metal structure made according to the present process. Figs. 14, 15 and 16 are diagrammatic views of a metal sheet illustrative of a modification that may be resorted to in the process. Fig. 17 is a diagrammatic plan view similar to Fig. 10 suggesting an arrangement of the die rollers or disks that may be used in carrying out the steps of the process according to Figs. 14, 15 and 16 of the drawings.
- 35 Like references designate corresponding parts in the several figures of the drawings.
- In carrying out the present invention, the first step in the process, as above indicated, is to simultaneously slit and expand certain 40 areas of sheet metal blank, such as the blank *a* shown in Fig. 1 of the drawings. This may be accomplished by any suitable mechanism or apparatus available for the purpose, but preferably by the means of coöperating 45 combined cutting and displacing dies *b* and *c* having the structural characteristics, arrangement, and operation of the dies disclosed in the patent to Herbert E. White, No. 1,049,632, dated Jan. 7, 1913. These 50 dies are diagrammatically indicated in Fig. 2 of the drawings, the upper dies being shown sufficiently depressed to illustrate the action thereof in cutting slits in the sheet metal and displacing or off-setting, to one 55 side of the plane thereof, the individual strands or cut-out portions. The first stage in this manipulation of the metal blank between the graduated dies of a die mechanism, such as that disclosed in said patent, 60 is to cut or slit the blank, in each slotted area, centrally of such area producing a middle series of alined and spaced longitudinal slits or cuts 1, as shown in Figs. 3 and 8. Then, this middle series of slits, in each 65 slotted area, is succeeded by the formation of

other parallel longitudinal slits designated by the numeral 2 in Figs. 5 and 8, and other figures. These other longitudinal slits 2 are cut into the metal sheet on both sides of the middle series of slits and are successively 70 made nearer and nearer to the margins of the sheet, while all of the slits, in each row thereof, are disposed in staggered or alternating spaced relation to the slits of adjacent rows.

In the combined slitting and expanding operation, a feature is the elongating or stretching of the strands of metal between the slits, accomplished by suitable instrumentalities such as suggested in the aforesaid patent to this applicant. The slitting and expanding step acts to displace all of the meshed web thus produced to one side of the plane of the original sheet, the said meshed web taking the form of a V-shaped 85 trough-like arch *d*. The result of this operation is to expand the slotted areas of the sheet, while at the same time stretching or elongating the metal in such portions. The stretching or elongating of the individual 90 strands serves to harden the metal to a certain extent, thus giving rigidity to the meshed or reticulated portions, and also effecting a saving of material without weakening the structure at any point.

When the combined slitting, expanding and deforming step is completed, the final step of the process is to subject the metal 100 shape of Figs. 7, 8, and 9 to a channeling or grooving operation that channels the blank unslotted areas *e* with relatively deep grooves which produce stiffening ribs between the expanded reticulated portions *d*. This rib-forming operation may be performed in any suitable manner and by any suitable instrumentalities, but for illustrative purposes there is suggested in Figs. 10, 11, and 12 of the drawings a means that may be resorted to for this step of the process. As diagrammatically illustrated in Fig. 10 of the drawings, a type of grooving and spreading machine that may be employed consists of a suitable number of graduated channeling or grooving units, each of which units may include successively arranged sets of upper 110 and lower complementary die rolls 3 and 4 respectively and suitable guides supported in stationary position between the succeeding sets of rolls. This is plainly shown in Fig. 10 of the drawings, and it will be understood that the die rolls will be arranged in parallel rows on parallel shafts, but necessarily are successively of a graduated construction to provide for progressively deepening and narrowing the grooves until the 115 same reach the full depth to provide the finished ribs *g*. As the unslotted and unexpanded portions of the sheet are drawn into ribs, the area of said portions will contract, but this contraction will be compensated for 120 125 130

by the fact that simultaneously therewith the expanded portions are taking the form of a straight line and their area in the original plane of the sheet is enlarged.

5 To illustrate the progressive development of the rib-forming grooves *f* to produce the stiffening ribs *g* between the expanded portions *d*, Fig. 11 of the drawings shows the engaging portions of the upper and lower die rolls 3 and 4 as they would appear at the feeding end of the grooving and spreading machine, while Fig. 12 shows these die rolls as they would appear at the delivery end of the machine where the rib-forming 10 grooves have reached their full depth and the slotted and expanded portions *d* have been spread or straightened into substantially the plane of the original sheet.

In the final product, as shown in Figs. 12 20 and 13, there is produced by reason of the specific manipulations described, an expanded section of a diamond meshed form between each pair of ribs, with the slats or strands of the mesh inclined at a considerable 25 angle to the flat plane of the structure, and the slats or strands at one side of the longitudinal center line of each meshed area being inclined reversely to the slats or strands at the opposite side of said line, although it 30 is understood that the present invention is not limited to this detail. Also, the process may be modified to meet certain conditions without departing from the invention. For instance, the process as illustrated by the 35 group of figures 1 to 10 inclusive, involves the feature of completing the lateral spreading of the expanded portions into the flat plane simultaneously with completing the rib-formation. A modification of this manipulation is shown in Figs. 14 to 17 inclusive 40 of the drawings, and presents one practical way of producing the structure when the formation of the ribs require more stock than the lateral spreading of the expanded 45 portions of the sheet will give. In explanation of this modification, it will be noted that Fig. 14 of the drawings diagrammatically shows the slotted and expanded sheet of the form shown in Fig. 7 with the intermediate 50 blank unslotted areas between slotted and expanded portions. By means of suitable instrumentalities, the blank unslotted areas of the sheet shown in Fig. 14 are grooved to 55 form the ribs *g* of the product, but before these ribs are completed to the desired form, the slotted and expanded portions *d* will have been laterally spread into substantially the plane of the original sheet. This stage of the modified process is shown diagrammatically 60 in Fig. 15 of the drawings, and in effect, represents the exact process already described, but as shown in Fig. 16 the rib-formation may be carried further to either

narrow or deepen the ribs, or both, to said desired form, and consequently narrowing 65 the sheet without, however, a further expansion or contraction of the expanded areas.

Although it will be understood that any instrumentalities or mechanism may be utilized in carrying out the modified process of 70 Figs. 14, 15 and 16, a suggested means is diagrammatically indicated in Fig. 17 of the drawings, wherein the graduated die rollers or disks 3 are shown as preferably disposed in parallel rows until the expanded areas are 75 drawn out into a flat plane, and from there on will converge until the ribs are brought into the predetermined form.

While Figs. 10 and 17 of the drawings diagrammatically suggest one form of rib-forming device, a preferable rib-forming mechanism that can be resorted to is shown in the applicant's Patent No. 1,056,871 dated March 25, 1913, wherein the bowed areas marked *w* in said patent bear the same relation to the 80 ribs as the bowed slotted and expanded areas in the present invention. Also other modifications in the process may be resorted to wherein the principle of the invention is retained. 90

I claim:

1. The method of making expanded metal structures which consists in slitting and stretching a longitudinal inside area of a metal sheet, leaving an uncut area on both 95 margins of the slotted area, and, simultaneously with the slitting operation, deforming the entire section of material between the uncut areas into a trough-form depressed to one side of the flat plane of the sheet, thereby 100 producing open meshes, and subsequently grooving the uncut areas to thereby produce ribs and to also thereby fully straighten the expanded troughed sections. 105

2. The method of making expanded metal structures which consists in slitting and stretching a longitudinal inside area of a metal sheet, leaving an uncut area on both 110 margins of the slotted area, and, simultaneously with the slitting operation, deforming the entire section of material between the uncut areas into a trough-form depressed to one side of the flat plane of the sheet, thereby producing open meshes, then grooving the uncut areas to thereby produce ribs and to 115 also thereby fully straighten the expanded trough sections, and subsequently giving to the ribs a final form to thereby produce a narrowing of the sheet.

In testimony whereof I hereunto affix my 120 signature in the presence of two witnesses.

HERBERT E. WHITE.
